Des. 220,493
Patented Apr. 20, 1971

220,493

CASSETTE FEEDING APPARATUS

Darrell S. Staley, Santa Clara, Calif., assignor to Ampex
Corporation, Redwood City, Calif.

Filed Apr. 1, 1970, Ser. No. 22,147

Term of patent 14 years

Int. Cl. D14—02, 03

U.S. Cl. D26—5

FIG. 1

FIG. 2

FIG. 1 is a front and left side perspective view of a cassette feeding apparatus showing my new design; and FIG. 2 is a right side elevation view of the apparatus, the top, bottom and back being conventionally plain.

I claim:

The ornamental design for a cassette feeding apparatus, substantially as shown and described.
